UNITED STATES PATENT OFFICE.

EDWARD B. HOUGH, OF PROVIDENCE, RHODE ISLAND, ASSIGNEE TO WIGHTMAN & HOUGH CO., OF PROVIDENCE, RHODE ISLAND, A CORPORATION OF RHODE ISLAND.

LOCKET.

1,126,217.

Specification of Letters Patent.

Patented Jan. 26, 1915.

Application filed May 4, 1913. Serial No. 765,254.

To all whom it may concern:

Be it known that I, EDWARD B. HOUGH, a citizen of the United States, and resident of the city of Providence, in the county of Providence and State of Rhode Island, have invented certain new and useful Improvements in Lockets, of which the following is a specification.

This invention relates to lockets, and has for its object to provide more particularly a so-called vanity case in the form of a locket, the same being adapted to carry a mirror in the inner side of the cover and a powder puff or other small article in the body thereof.

A further object of the invention is to provide the cover of a diameter smaller than that of the body portion and set into said body portion flush with the outer surface or contour thereof, and to provide this cover with an invisible hinge member connecting its inner side with that of the body portion, also to provide a spring to act upon this hinge so that when the cover is released by the catch member it will automatically open and expose the contents.

With these and other objects in view, the invention consists of certain novel features of construction, as will be more fully described and particularly pointed out in the appended claims.

Of the accompanying drawings: Figure 1— is a plan view illustrating the cover as of a smaller diameter than that of the body portion and flush with the contour thereof. Fig. 2— is a side elevation illustrating the cover set into the face of the body portion flush with its contour. Fig. 3— is an elevation showing the body portion in section and the cover in open position, also illustrating the mirror set in the cover and a spring for operating the catch member. Fig. 4— is a greatly enlarged plan view from the inside of the body portion, illustrating the hinge mechanism connecting the inner side of the cover to that of the body portion. Fig. 5— is a sectional side elevation of the casing showing the hinge member as connected at one end to the inner side of the cover and its opposite end pivoted to the inner side of the body portion, the cover being in closed position. Fig. 6— is the same as Fig. 5 with the cover in open position. Fig. 7— is a rear view of the casing partially in section illustrating the action of the spring

upon the hinge member. Fig. 8— is a sectional elevation of a portion of the casing showing the cam action of the releasing lever upon the catch which retains the cover normally in closed position.

Referring to the drawings 10 designates the body portion of the locket or receptacle which may be made in any suitable form, the same being preferably made in the form of a locket having a ring 11 by which it may be readily attached to a chain and suspended on a chain from the neck of the wearer. One feature of the invention is that the cover member 12 is made smaller in diameter than that of the body portion, the same being set into the body portion to rest upon an annular lip 13, the outer surface of the cover being flush with that of the body portion and preserving the general contour thereof without a break. The inner face of this cover is provided with an inwardly extending flange or lip 14 forming a bezel or collar in which is mounted a mirror 15. In order to hinge this cover to the body portion I have provided a substantially U-shape member 16, one end of which is permanently secured by solder or other means to the collar 14. The opposite end of this U-shape member is hinged by means of a pivot 17 between the ears 18 and this member is provided at its hinged end with a lip or curved finger 19 which is adapted to engage the spring 20 to throw the cover to open position when released by the catch.

The form of spring which I preferably employ is a piece of wire 20 normally straight, the middle portion of which is hooked under the finger 19 and the opposite ends are passed through the eyes 22, 22 on either side of the hinge portion and bent somewhat at its middle portion when under tension. The extreme ends of this wire extend beyond these eyes 22 and rest approximately against or near the inner edge of the locket whereby the wire is prevented from an endwise motion sufficient to be disengaged from its eyes 22 as the cover is worked back and forth. Another advantage of my improved construction is the arranging or mounting of this spring whereby it is very compact and takes up but little room in the locket, and at the same time its tension has the desired effect of opening the cover. Then again, if for any reason this spring should break it could be replaced by working the

end through the eyes 22 from the uncovered opening without the necessity of taking the locket apart. Then again, by my improved construction of hinge member the cover 5 when opened is carried completely clear of the opening and the bottom of the hinge member brings up against the edge of the locket forming a stop to retain the cover in a relatively upright position so that its mirrored surface may be readily variable and also to expose and permit the contents of the locket to be readily removed.

On the edge of the cover opposite the hinge I have provided a catch member 24, 15 the same extending through the collar 14 and slightly beyond the edge of the cover to engage the corresponding edge 25 of the body portion. This catch member is normally held pressed outward into engaging 20 position by means of the spring 26, see Fig. 3, one end 27 of which is passed through the inner portion of the catch member while the opposite end 28 rests against the opposite inner surface of the collar 14. This catch 25 member is also provided with a beveled inner face 29 adapted to be engaged by the cam-shape end of the lever 30 whereby when the presser end 31 of the lever is forced downward, its cam surface acts upon the 30 beveled surface of the catch member to force the same backward to disengage it from said edge and release the cover permitting it, under action of the spring, to swing to its opened position.

35 I claim:

1. A locket comprising a body having a top provided with a central opening, a cover for said opening provided with an annular flange, a substantially U-shaped hinge member secured at one side to said flange, means

connected to the underside of said top for pivotally supporting the other end of said hinge member, a spring also connected to the inner side of said top and acting on said hinge member to normally open the cover, 45 and means for holding said cover in closed position, said cover being of a size to fit flush with said top when in closed position.

2. A locket comprising a body having a top provided with a central opening, a cover 50 for said opening provided with an annular flange, a substantially U-shaped hinge member secured at one side to said flange and provided with a curved finger, means connected to the underside of said top for pivotally supporting the other end of said hinge member, a spring also connected to the inner side of said top and engaging said finger, and means for holding said cover in closed position, said cover being of a size to 55 fit flush with said top when in closed position.

3. A locket comprising a body having a top provided with a central opening, a cover for said opening provided with an annular 95 flange, pivoting means connecting said flange with the inner side of the top to permit the cover to fit flush with said top when in closed position, a spring acting to open said cover, a catch extending through 70 said flange, a complementary catch member on the inner side of said top, and a cam lever on the inner side of said top for disengaging said catch members.

In testimony whereof I affix my signature in presence of two witnesses.

EDWARD B. HOUGH.
